TRAILER ENGAGING HEAD MEMBER FOR
STABILIZING JACK

Henry M. Fredholm, Midlothian, Ill.

Application August 14, 1952, Serial No. 21,039

Term of patent 3½ years

(Cl. D41—1)

To all whom it may concern:

Be it known that I, Henry M. Fredholm, a citizen of the United States, residing at Midlothian, in the county of Cook and State of Illinois, have invented a new, original, and ornamental Design for a Trailer Engaging Head Member for Stabilizing Jack, of which the following is a specification, reference being had to the accompanying drawing, forming a part thereof.

Fig. 1 is an elevational view of a trailer engaging head member for stabilizing jack showing my new design.

Fig. 2 is an elevational view as observed from the right of Fig. 1, partially in section.

Fig. 3 is an elevational view as observed from the right of Fig. 2.

Fig. 4 is a bottom plan view as observed upon inversion of Fig. 3 and as usually observed when in stabilizing engagement with a trailer body.

The dominant feature of the instant design resides in

the dish-shaped outer head member and an inner disc-shaped head member providing therebetween an annular border and having adjacent the center thereof two butterfly wing-like embossments surmounting an annular U-shaped bracket.

I claim:

The ornamental design for a trailer engaging head member for stabilizing jack, substantially as shown and described.
